FIG. 5

The diagram illustrates a mechanical system with four parallel horizontal lines. The top line contains a spring labeled '11' and a stopper. The second line from the top has a component labeled 'SF' with a switch 'sk4' and a capacitor '1c'. The third line has a component labeled 'D' with a switch 'sk5' and a capacitor '2c'. The bottom line has a component labeled 'D' with a switch 'sk6' and a capacitor '3c'. The bottom-most line contains a component labeled 'P' with a switch 'sk1' and a capacitor '4c'. This line also features a vertical branch with a resistor 'R', a capacitor 'SK 6', and a switch 'sk2'. A vertical line labeled 'SCM' with a switch 'sk3' and a resistor '16' connects to the bottom line. A shaded rectangular area is labeled 'SCM' with a switch 'scm' and a resistor '15'.

UNITED STATES PATENT OFFICE

2,077,861

TELEPHONE SYSTEM

Reginald Taylor, Liverpool, England, and George Thomas Baker, Glamorganshire, Wales, assignors to Associated Telephone and Telegraph Company, Chicago, Ill., a corporation of Delaware

Application April 23, 1934, Serial No. 722,012
In Great Britain April 24, 1933

4 Claims. (Cl. 179—18)

The present invention relates to telephone systems and the main object of the invention is to provide improved facilities, to increase the reliability of such systems and to reduce the cost 5 of the apparatus required.

According to one feature of the invention, an automatic switch is arranged to be set to a particular position in response to more than a predetermined number of impulses, the impulses not 10 required for controlling the setting of the switch being used for sending a signal over the selected line.

According to another feature of the invention, a final selector for use in both preferred and non-preferred calls is arranged to test the selected line and to transmit back a signal to control a switching operation at a preceding stage when the selected line tests idle, said signal being the same on both types of call.

According to another feature of the invention, a telephone system includes secondary finders having access to overflow finders which have access to subscribers' lines and are only made available for use when all the regular primary finders 25 having access to the same subscribers' lines are busy and said secondary finders also have access to junctions incoming from another exchange.

According to a further feature of the invention, in a telephone system including primary and secondary finder switches marking potential is arranged to be extended from common control apparatus associated with the primary finders to mark a contact in the banks of the secondary finders and holding potential is subsequently fed 35 back to the primary finder over the same bank.

The invention will be better understood from the following description of one method of carrying it into effect, reference being had to the accompanying drawings, comprising Figures 1 to 40 14, which should be arranged as shown in Fig. 15.

Fig. 1 shows the trunking diagram of an 800-line R. A. X. (Rural Automatic Exchange). Figs. 2 to 8 show the line finder arrangement using the 45 partial secondary hunting feature, which was disclosed in United States Patent No. 1,914,540, issued June 20th, 1933.

Figs. 9 to 10 show a battery feeding first selector. Figs. 11 and 12 show a 200-line P. B. X. final selector arranged for toll (or trunk) offering, while Figs. 13 and 14 show an incoming selector which terminates a junction from the parent exchange and is accessible to both automatic subscribers and operators. It provides trunk offering 50 facilities for the latter over the regular final

selectors and has access to adjacent rural exchanges.

Before describing the operation of the circuits, it will be observed from the trunking diagram (Fig. 1) that the subscribers' lines SL are connected over the main frame MDF and the intermediate frame IDF, to the banks of 100-point primary line finders designated PF. The subscribers' meters are designated SM and the subscribers' line and cut-off relays are designated 10 LC.

These finders are connected with 10-level, 10-trunk, group selectors designated GS on the basis of partial secondary working. This means that 15 the finders PF are divided into two groups, regular and auxiliary, of which the regular finders RF are connected direct to regular group selectors RS, while the auxiliary finders AF are connected over the secondary finders SF to auxiliary group 20 selectors AS located in a common group, and accessible to all auxiliary finders in the exchange.

Direct junctions AE from adjacent exchanges, designated 4—8 are connected to bothway junction relay sets BWJ, and appear on the banks of the secondary finders SF over which they have 25 access to the auxiliary first selectors. This feature is particularly desirable from a traffic point of view since it enables use to be made of group selectors which would otherwise only be used during peak local conditions.

The junctions ME from the main exchange are similarly connected to bothway junction relay sets BWJ, and are terminated on individual incoming selectors IC, thereby obviating the necessity for multi-exchange area automatic subscribers and operators on the main exchange 35 waiting for a second dial tone when calling R. A. X.'s of this type.

For local calls the first selectors are digit absorbing and are provided with a transmission 40 bridge and they are also arranged to pass on discriminating signals according as the subscribers are in a regular or a coin-box group.

In the drawings, the levels 0, 1, 2, and 3 are shown as having access to four groups of 200-line 45 final selectors designated FS, thus giving a local capacity of 800 lines with a more regular numbering scheme than has hitherto been possible, while still leaving levels 4, 5, 6, 7, and 8 available for direct junctions to five adjacent rural exchanges, thus further simplifying the numbering scheme and permitting alternative routing to be effected in a simple manner, as will be described later.

The four figure numbers, adjacent to the banks 50

of the final selectors FS indicate the respective groups of subscribers served thereby.

It will be appreciated that the local line capacity can, if necessary, be increased to a maximum of 1,800 lines at the expense of one R. A. X. level for each additional 200 lines.

Outlets from level 9 are connected to the both-way relay sets BWJ1 associated with junctions to the main exchange, and the switch is arranged 10 to cut in on this level if either 9 or 0 is dialled, arrangements being made to prevent the selector stepping to the 0 level except when the first digit of a local number (2 or 3) has been previously dialled.

15 In the case of incoming junctions from the adjacent R. A. X.'s which require direct connection with the main exchange, the bothway junction relay set terminating the junction may be arranged in response to a characteristic signal to 20 set in operation a hunting switch TF shown dotted, to effect the desire through connection.

Referring to Figs. 2 to 8, it should be explained 25 that the finder circuits shown therein employ several of the features of the finder circuits shown in United States specification No. 1,914,540 issued June 20th, 1933. In the arrangement shown in the accompanying drawings, however, the primary finders are 100-line switches instead of 200-line switches and have access therefore only to 30 subscribers in their corresponding group.

When a call is originated in the A group only the start circuit is extended to the control relay sets of both groups of finders, relay ST is operated in the A group control relay set and relays 35 ST and SR are operated in the B group control relay set. Two finders are thereby taken into use for one call, but during this condition the B group control relay set has access to only A group finders so that the two finders selected are in the 40 A group. The reverse is true for a call originated in the B group.

If calls are originated simultaneously in both groups each control relay set will then have access to its own group of finders so that one finder 45 only is started in each group.

In the case of a breakdown of one of the control relay sets the other control relay set maintains the service by hunting over either the A group or B group of finders as determined by the 50 calling circuit.

The number of groups of finders controlled by each relay set may be more than two and the selection of a finder in the proper group may then be controlled by separate start relays.

55 During partial secondary working, the P wire is used first as a marking wire and subsequently as a guarding and holding wire, so as to free the D wire for use as a metering and discriminating lead.

60 Considering now the detailed circuit operation, when a subscriber connected to the line circuit shown in Fig. 2 originates a call, relay L is operated over the negative and positive lines in series with the substantial circuit and at armature l_1 marks the calling line in the rotary bank multiple of the finder, and at armature l_2 marks the calling level in the vertical bank multiple of the finder. The common start relay S is thus operated in parallel with the vertical bank marking 65 and at armature SI (Fig. 6) completes a circuit for operating the start relay ST of the A group control set to battery by way of the low resistance 70 10 . A branch circuit is also completed by way of the metal rectifier 2MRC for operating relay ISR in series with the start relay of the B group dis-

tributor and a portion of this circuit is shown enclosed in the dotted rectangle to the left of Fig. 6. It will be understood that the A and B group line finder distributor circuits are substantially identical with each other and the operation of relay 5 ISR in the B group distributor serves to change over the testing circuit so that this distributor will hunt over the A group of finders only during this condition. Metal rectifiers 1MRC and 2MRC are provided to separate the respective start 10 circuits and ensure that the respective SR relays are not operated from their own start circuits. Instead of using the metal rectifiers similar results may be obtained by employing a separate start relay for each group of finders. Certain armatures in the distributor circuit are placed in a circle to indicate that they belong to a relay in the other distributor.

Considering now the operation of the start relay ST of the A group, it will be seen that at 20 armature st_1 a battery testing circuit is completed via relay LK for the distributor switch ALD while at armature st_2 to st_4 circuits are extended for controlling the operation of the time cut-off relays TA and TB which will be described later. Due to the operation of armature st_1 the interrupter relay G operates over its left-hand winding in series with the left-hand winding of relay LK the latter remaining inoperative owing to the high resistance of relay G. Relay 30 G at armature g_1 (Fig. 7) completes a circuit for the driving magnet ALM of the distributor switch in series with the battery feeding relay BP. Relay G therefore interacts with the driving magnet ALM to rotate the wipers of the distributor switch in search of a free finder. It should be explained that all the regular and auxiliary finders of the A group are connected to the test bank $1a$ of the distributor switch, the auxiliary finders being normally bussed against 40 selection by earth extending from armatures of a relay RFB which is not operated until all the regular finders have been taken into use. The dotted strap in the drawings indicates the direct connection which is made for regular finders, 45 while in the case of auxiliary finders the circuit is completed over the armatures rb_4 to rb_6 of relay RFB and armatures rf_2 to rf_4 of relay RFZ when these relays are operated. The test bank $2a$ of the distributor switch has access when 50 required to all the regular and auxiliary finders in the B group and to prevent the switch from stopping in engagement with one of these finders when testing in the A group over bank $1a$, arrangements are provided to ensure that whichever test wiper is connected up there is no possibility of it coming to rest in engagement with a 55 finder of the opposite group.

For the purpose of this description it will first be assumed that regular finders are available and 60 therefore, the operation of the secondary finder apparatus shown in Figs. 5 and 8 will not arise at this time.

When the wiper $1a$ comes into engagement with a free regular finder, idle marking battery is 65 picked up over a circuit including the vertical wiper VW (Fig. 3) in its normal position over an I. D. F. connection shown in Fig. 4 to battery fed via resistance 11 (Fig. 5). This battery connection is sufficiently low in resistance to short-circuit relay G against further operation and relay LK therefore operates over both its windings in series and at armature lk_1 completes a holding circuit for itself over its low resistance right-hand winding which is sufficiently low in 70 75

resistance to guard the regular finder selected from other hunting switches. It will also be realized that during normal conditions and in the absence of a call, relay G may be operated 5 in series with the right-hand winding of relay LK to guarding earth picked up by wiper 1a. This causes the line finder distributor to perform a preselecting operation although it will be understood that the actual switching through as 10 described, is controlled over the battery testing circuit. The distributor therefore performs a double test on each contact to guard against false switching on to a disconnected finder.

Relay LK at armatures *lk2* and *lk3* completes 15 holding circuits to relay ST and at armature *lk3* (Fig. 7) operates relay VR. Relay VR at armature *vr1* operates relay E in the finder, at armature *vr2* operates relay SF in the control circuit from earth extended from the regular finder over the 20 dotted connection designated REG, at armature *vr3* operates relay C, and at armature *vr6* provides an alternative locking circuit for relay LK. Relay E in the finder with operating removes 25 earth from the common conductor 12 at armature *e1* (Fig. 3) to indicate the finder as busy to the secondary changeover relays RFB and RFZ (Fig. 7) and at armature *e2* prepares a circuit to the vertical magnet VM. Relay C at armature *c1* completes a circuit over wiper 6a 30 for relay H in the finder, which at armature *h3* completes the circuit to the vertical magnet VM and at armature *h8* (Fig. 3) connects direct earth to the testing bank of the distributor to mark the finder selected as busy. The vertical magnet 35 therefore energizes to raise the shaft and wipers to the first level and off-normal springs *N1* to *N3* are thereby operated; springs *N1* prepare a circuit to the release magnet ZM and springs *N3* prepare a circuit to the rotary magnet RM. At the 40 end of the vertical magnet stroke the interrupter springs *vm* (Fig. 3) close and provided the first level is not the one marked, a circuit is thereby completed over wiper 4a of the distributor for operating the interrupter relay G over its right- 45 hand winding. Relay G thereupon at its armature *g1* (Fig. 7) opens the circuit to the vertical magnet and interaction takes place between the two until the marked level is found, or alternatively, the wipers are raised to the 0 level. The 50 metal rectifier is connected so as to prevent the operation of relay VT from battery connected up by the interrupter springs *vm*.

When the marked level is found as indicated 55 by the connection of battery to the relevant contact in the vertical bank, relay VT (Fig. 6) in the distributor is operated in a circuit extending over springs *NR1* (Fig. 3) bank *3a* and both its windings in series with relay G which holds to maintain the vertical magnet circuit disconnect- 60 ed. Relay VT then locks over its upper winding which is sufficiently low in resistance to mark the vertical level selected as busy to other hunting switches, and at armature *vt2* opens the circuit to relay C (Fig. 7). Relay C releases after 65 its slow period and opens the circuit of relay H in the finder at armature *c1*, while at its resting armature *c2* relay RS is then operated and locked over an alternative circuit formed by way of armature *rs1*. Relay RS at armature *rs2* completes an alternative circuit for relay ST (Fig. 6) and at armature *rs3* (Fig. 6) disconnects relay VT and prepares a circuit to the rotary testing relay PA. Relay H in releasing transfers the impulsive circuit to the rotary magnet RM at 70 armature *h3* and also by connecting up earth at 75

armature *h7* short-circuits relay VT in the distributor which releases.

Upon the release of relay VT the rotary magnet RM of the finder is energized to rotate the wipers into engagement with the first contact 5 of the level selected. Normal rotary springs *NR1* and *NR2* operate when the shaft commences its rotary movement; springs *NR1* extend a connection from relay PA to the test wiper P of the line finder, and springs *NR2* close a point in the 10 release trunk conductor to the first group selector associated with this finder. It will be understood that the springs *NR2* are effective only in auxiliary finders and in the case of regular finders such as the one in question, they are 15 permanently short-circuited by the dotted strap 13.

At the end of the rotary magnet stroke the springs *rm* close and provided the first contact does not connect with the line marked, relay G 20 is again operated. Relay G thereupon inter-acts with the rotary magnet RM to rotate the wipers into engagement with the calling line. If the wipers fail to find the calling line they are rotated to the 11th step position where wiper P 25 engages contact *11s*. The finder switches through and then restores to normal. When the calling line is found the P wiper encounters battery from the line circuit and relay PA in the control set is operated in series with relay G which 30 holds. Relay PA re-operates relay C (Fig. 7) which locks in parallel with relay RS, at armature *c4* short-circuits relay LK (Fig. 6) and at armature *c1* re-operates relay H (Fig. 4) in the 35 finder. Relay H in operating, at armatures *h1* and *h2* extends direct earth to the P wiper and this brings about the operation of relay K in the line circuit in series with relay L which holds. Relay K in the line circuit opens the start 40 circuit to relay S and clears the battery and earth connections from the calling line which is then extended over the armatures *h4* and *h5* to the selector associated with the line finder, for example, that shown in Figs. 9 and 10.

As will be described later, in response to the 45 switching-through of the calling line, the associated group selector is prepared for the reception of the dialled impulses and it accordingly extends dialling tone over the lower speaking conductor to the calling subscriber, and returns 50 earth potential over the P wire to hold the switching relay H of the finder and the L and K relays in the line circuit. As a result of the short-circuiting of relay LK this relay releases and in 55 turn releases the control set and the wipers of the distributor switch ALD are then stepped onto the next set of contacts.

Consideration will now be given to the case 60 when all regular finders in the group are in use, so that a further call will have to be completed over one of the auxiliary finders and for this purpose use is made of the secondary equipment shown in Figs. 5 and 8 which performs a hunting operation to associate one of the selectors in the common group with the auxiliary finder taken 65 into use. When all the regular finders are taken into use, earth will be disconnected from the common conductor 12 which connects with the resting off-normal springs *N1* (Fig. 3) of all the regular finders in the associated group and consequently when the battery feeding relay BP (Fig. 7) again operates as the distributor kicks on at the termination of the previous connection a circuit is completed for energizing relays RFB and RFZ (Fig. 7) in parallel. It will be appreciated 70 that up to this time these relays have been short- 75

circuited against operation by the earth on the common conductor 12. Relay RFB at its armature *rfb1* provides a locking circuit for both relays, and at armatures *rfb4*, *rfb5* and *rfb6*, *rfz1*, 5 *rfz2*, *rfz3* and *rfz4* (Fig. 6) the testing circuit for the distributor is extended through to the corresponding auxiliary finders. It should be explained that as soon as all regular finders in a primary group become busy, the whole of the 10 group of secondary finders having access to the auxiliary finders of this particular primary group is opened up, so that secondary distributors such as SDS (Fig. 8) are caused to preselect idle secondary finders such as SCF (Fig. 5) and the 15 manner in which this is effected will now be described.

Relay RFZ in operating, at armature *rfz6* (Fig. 8) connects earth to a common conductor 14, extending to the OB relays of all secondary start 20 groups such as SSI, which for the purpose of this description may be assumed to be two in number. It should be explained that the conductor 14 extends at one end to the OB relays of all secondary start groups and extends at the other end to 25 armatures *rfz6* of all primary distributor groups with which the secondary start groups are associated.

Assuming that at least one secondary finder SF is available in the group, relay OB will be 30 operated over the following circuit: earth on common conductor 14, metal rectifier 4MRC winding of relay OB, common conductor 15, resistance 16 (provided one per secondary finder) 35 armatures *sk3*, *sk2* and *sk1* to battery by way of the resistance 17 (also one per secondary finder). Relay OB at armature *ob1* connects earth to a common conductor 18 to short-circuit relay EB which is common to the whole exchange, and at armature *ob2* operates relay FB. Relay FB at 40 armatures *fb1* and *fb2* removes earth from the leads 19 and 20 which are connected to common terminals on the distributing frame IDF from which connections extend to the auxiliary finders, and replaces this with idle marking battery by 45 way of the windings of relay DS. Relay FB, also at armature *fb3*, completes a preselecting circuit for the secondary distributor switch SDS and at armature *fb4* completes a similar preselecting circuit to secondary distributor switch No. 2 previously referred to. Both secondary distributors therefore, hunt to find a free secondary finder as indicated by the absence of earth on the contacts encountered by wiper 4b. If the secondary distributor switch shown is standing in 55 engagement with a secondary finder which is already in use, wiper 4b will encounter earth from the armature *sk2* and this operates the interrupter relay GG in series with the upper low-resistance winding of relay DK. Owing to its high resistance, relay GG only operates in this 60 circuit and thereupon interacts with the driving magnet SDM to rotate the wipers into engagement with a free secondary finder as indicated by absence of earth. By this means two idle secondary finders are preselected for use and no further circuit operations take place until another call is originated. When this occurs the subscriber's start circuit is again extended to the primary distributor as already explained and the switch ALD thereupon selects an idle auxiliary 65 finder over wiper 1a. Relay LK then operates and the following circuit is completed: earth armature *lk1*, low resistance right-hand winding of relay LK, armatures *tb2*, *ofb3*, *sr2*, wiper and bank 1a, armatures *rfb4* and *h8*, wiper VW, 70 terminal S on the distributing frame, conductor 75

20, armature *fb2*, lower winding of relay DS to battery. Relay DS operates and shunts armature *fb2* by armature *ds2*. At the same time the operation of relay VR (Fig. 7) in the distributor circuit extends a marking battery by way of the 5 high resistance relay SF in parallel with the low resistance 21 over armature *vr2*, wiper and bank 7a, and over the conductor P to mark the position of the auxiliary primary finder selected in the bank multiple of the secondary finder. Similar 10 operations take place in the other primary distributor. The hunting operation of the two auxiliary finders continues without interruption until the calling line is located, but at this stage the switching through of the finders is suspended 15 since there is no circuit for operating the controlling relays SF until one of the secondary finders locates the corresponding auxiliary finder.

Considering again the operation of the secondary finder equipment, relay DS in operating at 20 armature *ds3* completes a switching circuit for relay DK in the secondary control group SC1, and at armature *ds4* completes a similar circuit for the other control group. As regards the control group SC1 it will be seen that relay DK is operated over 25 both its windings in series to battery by way of resistance 17 in the secondary finder and thereupon at armature *dk1* provides a holding circuit for itself over its upper winding which is sufficiently low in resistance to guard the secondary finder 30 selected. Relay DK moreover at armature *dk2* prepares a circuit to the fast operating test relay DK and at armature *dk3* completes a self-interrupting driving circuit to the magnet SCM of the 35 secondary finder from earth at armature *fk1*. Both secondary finders therefore, hunt at high speed to locate the auxiliary finders, and the fact that their wipers will probably be displaced relatively to each other since they are non-homing switches considerably reduces the finding time. 40

When the successful auxiliary finder is found, relay FK connected to the successful secondary finder operates quickly and disconnects the hunting circuit at armature *fk1*. At the same time it removes the short-circuit from relay FR which 45 operates over its comparatively high resistance winding in series with the driving magnet SCM, and then locks independently by way of its armature *fr1*. Relay FR also opens a point in the circuit to relay GG at armature *fr2* and at armature 50 *fr3* completes a circuit for operating the switching relay SK in the secondary finder. Relay SK in operating at armature *sk2* and *sk3* marks the secondary finder as busy to the distributor equipment, and at armatures *sk1*, *sk4*, *sk5* and *sk6* 55 extends the P, negative, positive and D wires from the auxiliary finder to the first selector. Relay SF in the primary distributor is also operated in series with the left-hand winding of relay SK and brings about the switching through of the 60 auxiliary finder in the manner already explained. The calling subscriber's circuit is now extended through to the first selector which accordingly returns dial tone and connects direct earth to the P wire to hold relays K and L in the line circuit, 65 relay H in the primary finder and relay SK in the secondary finder. Relay FK in the secondary distributor circuit is short-circuited and released by this earth and in turn short-circuits relay FR which thereupon releases whereupon the switch 70 SDS immediately preselects the next available secondary finder.

If all the auxiliary finders in the A group become busy, relay OFB in the distributor circuit (Fig. 7) is operated when the last auxiliary finder 75

switches through, and at armature $ofb1$ opens a point in the circuit to the start relay ST, at armature $ofb2$ transfers the start earth to conductor 22 leading to an overflow meter not shown, and at 5 armature $ofb3$ transfers the test circuit to wiper 2a which searches over B group finders. Consequently further calls from the A group of subscribers cannot be completed and are diverted so as to operate the overflow meter. It will be 10 understood however that the distributor equipment of the A group is still responsive to calls originated in the B group of subscribers, and for this purpose the circuit of the start relay ST is maintained over the armature $ofb1$ shown enclosed in a circle, to indicate that it is associated with the OFB relay in the B distributor. The armature $1bp1$ (Fig. 7) is also associated with the B group distributor and is provided for a similar purpose.

20 In case all secondary finders become busy there will be no circuit for operating the OB relays (Fig. 8) and consequently the common relay EB is operated. This relay is provided with a number of armatures similar to armature $eb1$ (Fig. 6) 25 and on operation these disconnect the start battery from the respective primary distributors to prevent them functioning during this condition.

In case for any reason a selected finder fails 30 to find the calling line within a predetermined period of time the cut-off relays TA and TB (Fig. 6) will function to give an alarm, and busy the faulty finder from further selection. The circuit operations which take place will now be 35 described.

35 It will be remembered that when the start relay ST (Fig. 6) operates, a circuit is completed for starting up the S and Z pulse cams and the lower winding of relay TA is connected to the S pulse cam. When the S pulse is received relay TA operates and locks over its upper winding and connects the upper winding of relay TB to the lead extending to the Z pulse cam. If the finder selected fails to find within a prescribed period the Z pulse 40 operates relay TB which locks over its lower winding and lights the alarm lamp ALM. Relay TB also disconnects the hunting circuit of the distributor at armature $tb2$, and at armature $tb6$ connects earth to a common conductor 23 extending to a common alarm circuit not shown. Moreover 45 at armature $tb5$ earth on the wiper 2a in the distributor is connected to the wiper 1a to busy the faulty finder, and at armature $tb4$ (Fig. 7) relay H in the finder is operated to disconnect earth 50 from the common conductor 12 at armature $h1$ so as to mark this finder as busy to the overflow relays RFB and RFZ. These conditions obtain until such time as the fault is cleared, whereupon the attendant releases the equipment by operating the re-setting key T in the distributor circuit.

55 Upon the release of the connection when the calling subscriber replaces his receiver, earth is removed from the release trunk conductor P by the controlling switch in the train, and relay H in the primary finder and relay SK in the secondary finder release as also do relays K and L in the subscriber's line circuit. A circuit is thus 60 complete for the release magnet ZM of the primary finder which restores the wipers to normal, while the release of relay SK connects up the idle marking battery 17 to mark the secondary finder as free for further use.

65 Referring now to Figs. 9 and 10 when the first selector shown is taken into use from the finder or its equivalent over the negative and positive

conductors, relay 1A operates and at armature $1a1$ in turn operates relay 1B and 1C in parallel. Relay 1B at armature $1b1$ connects earth to the release trunk conductor P to guard the circuit and hold operated the switching relay in the preceding circuit, and at armature $1b2$ connects dial tone to the lower speaking conductor to inform the calling subscriber that he may now commence to dial. Relay 1C is operated to prepare the impulsing circuit.

10 In the case of calls to the manual board, subscribers dial the digit 0 whereupon relay 1A responds and repeats the impulses through the low resistance winding of relay 1C to the vertical magnet 1VM which energizes to raise the shaft 15 and wipers to the desired level. Off-normal springs 1N1-1N5 are operated when the shaft leaves its normal position and are without immediate effect except for opening the initial energizing winding of relay 1C, which however, remains held during the impulsing in series with the vertical magnet over its lower winding. Relay 1B is similarly held during the impulsing period by reason of the copper slug surrounding its core. When the shaft and wipers reach the 20 9th level the vertical wiper 1VW (Fig. 9) will also come into its 9th position, and when relay 1A again operates at the end of the 9th impulse, relay 1W then operates over the vertical bank and 25 armatures 1c6 and 1ws3 in series with the vertical magnet 1VM which is inoperative in this circuit. Relay 1W at armature 1w1 disconnects the impulsing circuit to the vertical magnet so that the 10th impulse is not effective as regards 30 raising the shaft and wipers and serves to operate 35 relay 1MC which locks. It will be appreciated that this principle whereby certain of the impulses control the setting of a switch and the remainder control a different operation is capable 40 of wider application. If the second portion of 45 the impulse series comprises more than one impulse, they may be registered by an auxiliary switch or counting relays which may subsequently control the transmission of different signals in accordance with their setting. Such auxiliary apparatus may be associated in common with a group of switches.

At the end of the impulsing period relay 1A remains held and relay 1C releases after its slow 50 period and releases relay 1W. A circuit is now 55 completed to the rotary magnet 1RM for advancing the wipers into engagement with the first trunk of the 9th level, and the circuit may be traced from earth at armature $1b7$ (Fig. 10) armatures 1w4, 1mc5, 1g2, 1h3, 1cc5, springs 1N3, 55 armature 1b4, winding of rotary magnet 1RM to battery. Normal rotary springs 1NR1 and 1NR2 are operated during the first rotary step but are without immediate effect. If the first trunk is engaged the P wiper encounters earth and when 60 the rotary magnet springs 1rm close relay 1G is then operated over its upper winding to earth 65 extended over wiper P and armatures 1h1 and 1b6. The same earth also short-circuits the switching relay 1H to prevent it from operating during these conditions. Relay 1G at armature 1g2 disconnects the rotary magnet circuit and when the rotary magnet springs 1rm open, relay 1G releases to again complete the magnet circuit and this action continues automatically until an idle outlet is found or the wipers reach the 70 11th position.

75 When an idle outlet is found as indicated by the absence of earth potential on the contact engaged by the P wiper, the switching relay 1H 75

operates in series with relay **IG** but the latter remains inoperative owing to the high resistance of relay **IH**. Relay **IH** at armatures **1h1** and **1h2** completes a locking circuit for itself in series with the vertical magnet **IVM** which is also inoperative, at armature **1h3** disconnects the circuit to the rotary magnet **IRM**, and at armature **1h4** releases relay **IMC** and operates relay **ISW**. Relay **ISW** at armature **1sw1** provides a locking circuit for relay **IH** after the release of relay **IMC**, at armature **1sw2** extends a connection from armature **1mc4** to the wiper **D**, and at armatures **1sw3** to **1sw6** disconnects the battery feeding bridge in the selector and extends the calling circuit straight through to a relay set (not shown) connecting with a junction to the parent exchange. Relays **1a** and **1B** are now released but before the release of the latter the relay set returns guarding and holding earth over the **P** wiper and bank contact to hold the switching relay **IH**. As explained relay **IH** also releases relay **IMC** but the latter owing to its slug remains held for a short period, sufficiently long to extend a signal over the **D** wiper to the relay set selected, thereby indicating that this call is intended for the manual board. This causes the relay set to extend a manual board calling condition to the parent exchange. When relay **IMC** eventually releases the **D** lead is connected straight through to the calling line circuit and in the case of regular subscribers then serves as a metering lead, the metering being controlled from the relay set.

If the called party is a coin box subscriber, the **D** lead is connected to a high resistance battery in the line circuit instead of to the meter, so that battery is maintained on the **D** lead after the release of relay **IMC** and constitutes a coin box signal to the relay set, thereby causing it to extend a different class of signal to the parent exchange to indicate that the call has been originated by a coin box subscriber.

If all the outlets are engaged the wipers rotate to the 11th step where cam springs **1S1**-**1S3** are operated; springs **1S1** short-circuit the switching relay **IH** to prevent its operation, springs **1S2** close a locking circuit for relay **IG** to cut off the rotary hunting circuit, and springs **1S3** (Fig. 9) connect busy tone by way of a condenser to the lower speaking conductor to inform the calling subscriber that the connection is unavailable. Subscribers requiring connection with automatic switches in the parent exchange dial the digit **9** whereupon the wipers are stepped to the 9th level, where relay **IW** operates as in the case when the digit **0** is dialled. Since, however, there is no 10th impulse, relay **IMC** remains normal and when relay **IC** restores at the end of impulsion the wipers automatically cut in on to the first outlet. From this point the operations proceed as previously described except that when a free outlet is found and relay **IH** switches, no signal is connected to the **D** wiper because of the non-operation of relay **IMC** and consequently the relay set selected extends the automatic calling condition to the parent exchange. Single or zone metering is controlled from the relay set over the **D** lead.

For calls to an adjacent rural exchange, the dialling of the first digit of the prefix raises the wipers to the desired level and when relay **IC** restores, the switch hunts for a free outlet in the manner previously described.

When a free outlet is found, relay **IH** switches and extends the calling circuit to the associated relay set which provides the transmission bridge

and controls metering. If alternative routing is provided, the outlets immediately following those associated with direct junctions are connected to relay sets associated with junctions to the parent exchange, so that in the event of all direct junctions being found busy the selector continues to hunt over the same level to select a junction to the parent exchange. For this purpose a two or three digit prefix is allocated to the adjacent R. A. X's and arrangements are made for suppressing certain of these digits when a direct junction is selected, whereas if the call is routed via the parent exchange all digits are effective in setting up the required route. In the drawings the vertical bank is shown typically wired so that levels **1** and **8** serve R. A. X's in the single fee area and levels **4**, **5** and **6** serve R. A. X's in the excess fee area.

When the switch is taken into use by a coin box subscriber relay **ICB** is operated over the **D** lead from the discriminating battery in the line circuit and thereupon locks over its light armature **1cb1** for the remainder of the connection. It will be assumed that the coin box subscriber dials an excess fee area. When relay **IC** releases at the end of the digit, relay **ICC** is operated over the vertical bank and vertical wiper in position **4**, **5**, or **6** and locks by way of its armature **1cc1** and at armature **1cc2** (Fig. 10) operates relay **IMC** which also locks and completes a circuit for the vertical magnet **IVM** which may be traced from earth at armature **1b1** (Fig. 10) armatures **1w4** (Fig. 9) **1mc5**, **1c5**, **1g2**, **1h3**, **1cc5**, winding of magnet **IVM** to battery. The vertical magnet therefore energizes to raise the shaft and wipers to the next level and at the end of the magnet stroke the springs **1vm** close and operate relay **IG** over its upper winding. Relay **IG** in turn opens the circuit to the vertical magnet **IVM** at armature **1g2** and interaction takes place between the two until the wipers are raised to the 9th level.

In this position earth on the vertical bank holds the vertical magnet **IVM** over a comparatively low resistance **30**, and during the holding period relay **IW** is operated to release relay **ICC**. Relay **ICC** releases relay **IW** and in turn the vertical magnet whereupon the wipers cut in over the 9th level and proceed to select a relay set associated with a junction to the parent exchange. The operation of relay **IMC** results in a manual calling condition being extended to the parent exchange together with the coin box signals so that the call is routed to the manual board as described in the case of the dial "0" call.

Local numbers consist of four digits commencing with either **2** or **3**, the first digit serving to prepare the circuit for pre-switching the wipers of the final selector on to the correct hundreds group of lines when it is subsequently taken into use.

If, for example, the digit **3** is dialled the selector steps to the 3rd level where the normal post springs **1NP1** (Fig. 10) operate and in turn energize relay **IW** when relay **IC** releases at the end of the digit, over the following circuit: battery, winding of vertical magnet **IVM**, winding of relay **IW**, armatures **1w3** and **1c6**, springs **1NP1**, armature **1b1** to earth. Relay **ICB** is also operated over the vertical wiper and bank armatures **1cb3**, **1c1**, **1b7**. Relay **ICB** locks up and in conjunction with relay **IW** completes the following circuit for the release magnet **IZM** which restores the shaft and wipers to normal: battery, winding of release magnet **IZM**, armatures **1w5**, and **1cb3**, bank contact and vertical wiper **IVW**, armatures **1cb1** and **1b7**.

to earth. To ensure a reliable release operation the release magnet is caused to lock through its own contacts $1z\bar{m}1$, and operated off-normal springs $1N2$.

5 When the shaft and wipers have fully restored, the springs $1N2$ will again become normal, and during the slow releasing period of relay $1W$, relay $1WS$ is operated and locked, thereby at armature $1ws5$ disconnecting dial tone 10 from the lower speaking conductor and at armature $1ws6$ preparing a circuit for relay $1MC$. The next digit steps the first selector to the level having access to the required group of final selectors, relay $1MC$ operates when armature $1a1$ 15 falls away in the first impulse and locks over armature $1mc1$ and off-normal springs $1N1$. At the end of the digit when relay $1C$ falls away, the selector proceeds to select an outlet to an idle final selector and when this is found relay 20 $1H$ switches as previously described. Relay $1SW$ is not operated in these circumstances but as relay $1WS$ is energized a circuit is completed for relay $1W$ as follows: battery, winding of vertical magnet $1VM$, winding of relay $1W$, armatures $1ws3$, $1\bar{w}5$, $1ws4$ and $1\bar{w}4$, springs $1N1$, armature $1b1$ to earth. Relay $1W$ thereupon locks over its own armature $1w3$ and subsequently functions as a meter delay relay. Upon the application of earth to the negative wiper and bank 25 contact by the operation of armature $1h7$ a circuit is complete for operating the line relay in the final selector taken into use, for example, relay $2A$ in Figs. 11 and 12 which in turn operates relays $2B$ and $2C$. Consequently during the 30 slow releasing period of relay $1MC$ the battery connected to the discriminating wiper D over armatures $1cb4$, $1mc3$, $1h6$ and $1sw2$ serves to operate the wiper switching relay $2WS$ in the final selector which transfers the incoming wires 35 to the set of wipers having access to the second hundreds group of lines.

If, however, the digit 2 had been dialled instead of 3, relay $1CB$ in the selector would not have been operated and the wiper switching operation described would not therefore take place connection being then made with the wipers of the first hundred line group. The tens and units digits are now dialled and repeated by relay $1A$ in the group selector over the negative wiper and bank to the line relay in the final selector which is thus set to the required level.

If the required subscriber is free the final selector connects a momentary battery to the positive line thus operating relay $1SD$ in the first 45 selector (Figs. 9 and 10) which completes a locking circuit for itself, and at armature $1sd3$ completes a ringing circuit by way of the right-hand winding of relay $1F$ to the called subscriber's line. During the ringing period a ring back tone 50 connected up by the operated armature $1sd5$ is applied to the positive speaking conductor to the calling subscriber to inform him that the called subscriber is being rung. When the called subscriber replies, relay $1F$ is operated from battery superimposed on the ringing circuit and in 55 operating its armature $1f1$ thereupon locks for the remainder of the connection over its left-hand winding, and at armatures $1f2$ and $1f3$ completes the transmission circuit between both 60 subscribers. Relay $1D$ is operated over the called subscriber's circuit and at armatures $1d2$ and $1d3$ reverses the battery connection to the calling side of the circuit for metering or supervisory purposes, and at armature $1d1$ opens the circuit 65 of relay $1W$. Relay $1W$ in turn opens the circuit 70

to relay $1SD$ at armature $1w3$ and during the slow release period of the latter relay, battery is connected to the D lead to operate the calling subscriber's meter. It will be noted that the slug on relay $1W$ renders this relay insensitive to momentary flicks of relay $1D$ which may occur during the setting up of the connection, thereby guarding against false metering. 75

If the called subscriber is engaged, the final selector does not connect battery to the positive line but instead removes earth from the release trunk conductor P so that relay $1H$ in the first selector restores. Relay $1H$ thereupon opens the circuit to the final selector which is completely released but the first selector remains 10 held to transmit busy tone to the calling subscriber and this is connected up to the positive speaking conductor during this condition over the operated armature $1w2$.

In this example, the final selectors are assumed 15 to be connected to levels 0, 1, 2, and 3 of the first selector. Consequently, if the subscriber dials 2 or 3 as the first digit and follows these by a digit which does not correspond to a level connecting with the final selectors, then the earth 20 over the vertical bank and wiper, armatures $1cb2$ (in the case of levels 4, 5, and 6) and $1ws7$ and interrupter springs $1rm$ operate relay $1G$ when cut-in takes place, and cause the wipers to be rotated to the 11th step to set up the busy 25 condition as described.

Release of the connection is controlled by the calling party and is brought about when he replaces his receiver on the switchhook, and it will be noticed that arrangements are made for 30 earthing the release trunk conductor P from operated release magnet springs $1z\bar{m}2$ in order to maintain the switch guarded against re-seizure until it has fully restored to normal.

Provision is also made for slipping the first 35 selector bank multiple between switches or in the grading between shelves so that the first choice junction on respective switches will be different. This arrangement ensures the satisfactory completion of a repetition call in the case 40 of a faulty junction since the next first selector taken into use selects a different first choice junction.

Referring now to the P. B. X final selector 45 shown in Figs. 11 and 12, when this switch is taken into use from the preceding group selector already described, relay $2A$ operates over the negative line and in turn operates relay $2B$ which at armature $2b1$ returns guarding and holding earth over the P wire, and at armature $2b2$ 50 operates relay $2C$ over its right-hand winding and springs $2N1$ and $2N\bar{R}1$. Relay $2WS$ is thereupon connected to the D lead over armatures $2b3$ and $2c1$ and if the call is for a subscriber in the second hundreds group of lines, the application of the battery pulse to the conductor in the group selector operates relay $2WS$ which locks and connects up the required set of wipers. When the tens digit is dialled, relay $2A$ responds and intermittently energizes the vertical magnet 55 $2VM$ in series with the low resistance left-hand winding of relay $2C$. The shaft and wipers are thereby raised to the desired level, off-normal springs $2N1$ to $2N3$ are operated when the shaft takes the first step and at springs $2N1$ the initial 60 energizing circuit is opened to relay $2C$. It will be noted, however, that this relay remains held throughout the impulsive period by reason of the copper slug surrounding its core and the intermittent energization of its left-hand wind- 65

ing in series with the vertical magnet. Relay 2B is also held by reason of the copper slug surrounding its core.

At the conclusion of the tens series of impulses, relay 2C releases after its slow period and completes a circuit for operating relay 2E which locks, at armature 2e5 transfers the impulsive circuit to the rotary magnet 2RM and at armature 2e2 re-operates relay 2C. The units series of impulses are therefore received on the rotary magnet 2RM which rotates the wipers into engagement with the required line. Rotary off-normal springs 2NR1 to 2NR3 are operated when the shaft takes the first rotary step and at springs 2NR1 the initial energizing circuit of relay 2C is again opened so that this relay now holds for the remainder of the digit on its left-hand winding in series with the rotary magnet.

If the line dialled is the first of a P. B. X group, relay 2HS is operated and locked over the miniature wiper and bank PBX when relay 2C restores. The miniature wiper and bank is of well-known construction and comprises a 100-point contact bank consisting of 10 rows of 10 contacts which are wiped over by a pair of trailing wipers attached to the switch shaft, the blades of which are arranged to establish connection with adjacent contacts in the same level at the same instant. In this bank all contacts corresponding to PBX groups except the last contact are strapped together and connected to earth as shown, through a resting armature 2h3 of the switching relay 2H. It will further be noted that PBX groups can only be allocated in the second hundreds group of lines, that is, when relay 2WS is operated to connect up the lower set of wipers.

When relay 2C releases at the end of the units series of impulses, it opens the locking circuit of relay 2E at armature 2c6 and during the slow releasing period of the latter a circuit is prepared to the switching relay 2H over armatures 2h3, 2b2, 2e1 and 2c7 for testing the condition of the first line in the group. If the line is free, relay 2H operates in series with the cut-off relay in the called subscriber's line circuit and locks to earth on the release trunk conductor P. If, however, the first line is busy the test wiper will encounter earth in place of battery so that the switching relay 2H will not operate, and when relay 2E restores, a circuit is again completed to the rotary magnet 2RM which now energizes in a series circuit including the low resistance right-hand winding of relay 2HS and the left-hand winding of relay 2C. The wipers are therefore stepped on to the next set of contacts and relay 2C again operates.

At the end of the magnet stroke when the interrupter springs 2rm close, relay 2E again operates and locks as before, thereby disconnecting the rotary magnet circuit and when relay 2C releases the testing circuit is again completed for the switching relay 2H. This action continues automatically until an idle line is found or alternatively the last line in the group is found to be engaged. It will be noticed that during the movement of the miniature PBX wipers from contact to contact, relay 2HS is held operated over its low resistance right-hand winding in series with the rotary magnet.

When an idle line is found, relay 2H operates and locks as described, and at armature 2h4 and 2h5 prepares for the extension of the calling circuit to the required subscriber's line. Relay 2A thereupon releases and disconnects relay 2B

and during the slow releasing period of the latter, battery is connected to the positive line over armature 2b5 to signal the first selector that the called line is idle. The first selector thereupon proceeds to transmit ringing current and provides a speaking circuit in the manner previously described. 5

If all the lines in a group are busy, the wipers rotate to the last line where the leading wiper of the PBX bank comes out of engagement with the common set of contacts and relay 2HS thereupon restores. During the slow releasing period of relay 2E of the last line is tested in the manner described and as this is assumed to be busy relay 2H will not operate and upon the release of relay 15 2E earth is disconnected from the release trunk conductor P to indicate to the group selector that the connection is unavailable. The group selector thereupon returns a busy signal to the calling subscriber and the final selector is released in the manner previously described. 20

If, however, the call has been set up over an incoming selector, for example, that shown in Figs. 13 and 14, which is provided with trunk offering facilities, it is necessary that the final 25 selector shall remain held even though the line selected proves busy, and this is achieved as follows.

When the holding earth is disconnected from the negative conductor by the release of the 30 switching relay in the group selector, relay 2A in the final selector releases and in turn opens the circuit to relay 2B. During the slow release period of relay 2B a circuit is completed over armatures 2a1, 2b4, 2h5, and 2e5 for relay 2C 35 which operates over its right-hand winding and as earth is still connected to the D lead extending from the group selector, relay 2H in the final selector is thereupon operated over its upper winding from battery connected up at armature 40 2c4 and completes a holding circuit for itself over its lower winding to earth which is subsequently connected to the P wire extending from the incoming group selector in a manner which will be described later. The final selector is 45 therefore prevented from releasing when relay 2C restores and a cut-in circuit is provided over the busy connection for trunk offering purposes, as will be described later.

Referring now to the incoming selector Figs. 13 50 and 14, when this switch is taken into use over an incoming junction from the parent exchange, relay 3A operates in series with the differential relay 3OC which remains normal. Relay 3A at armature 3a1 (Fig. 14) operates relays 3B and 3C in parallel and the latter at armature 3c3 (Fig. 13) lights the supervisory lamp LP. If the call is for an adjacent exchange, the first digit e. g. 6 of the prefix for the desired exchange is dialled, whereupon relay 3A responds and repeats 60 the impulses through the low resistance upper winding of relay 3C to the vertical magnet 3VM which energizes to raise the shaft and wipers to the desired level. Off-normal springs 3N1 to 3N4 are operated when the shaft leaves its normal 65 position and are without immediate effect except for opening the initial energizing winding of relay 3C which however, remains held during impulsive in series with the vertical magnet 3VM. Relay 3B is similarly held during impulsive by reason of its copper slug. Relay 3C restores at the end of the impulse train, and completes a rotary cut-in circuit to the magnet 3RM by means of which the wipers are advanced into engagement with the first trunk of the level selected. The 70 75

circuit for this operation may be traced from earth at armature 3hr2 (Fig. 13) armatures 3b1 and 3c2, vertical wiper and bank 3VW, armatures 3ws2 and 3g3, springs 3N4, winding of magnet 3RM to battery. As soon as the shaft commences its rotary movement normal-rotary springs 3NR1 to 3NR2 are operated thereby at springs 3NR1 (Fig. 14) completing a circuit over its right-hand winding for relay 3DS which operates, but 10 without immediate effect.

If the first trunk in the level selected is engaged the P wiper encounters earth and when the rotary magnet springs 3rm close at the end of the magnet stroke, relay 3G is operated over its lower winding. The same earth also short-circuits the switching relay 3H to prevent it from operating during these conditions. Relay 3G at armature 3g3 disconnects the rotary magnet circuit and when the rotary magnet springs 3rm open, relay 3G releases to again complete the magnet circuit and this inter-action continues automatically until an idle outlet is found or the wipers reach the 11th position.

When an idle outlet is found as indicated by the absence of earth potential on the P wiper, the switching relay 3H operates in series with relay 3G but the latter remains inoperative owing to the high resistance of relay 3H. Relay 3H at armature 3h1 completes a locking circuit for itself in series with the vertical magnet 3VM which is also inoperative, and at armature 3h3 operates relays 3SW and 3HR in parallel. Relay 3SW at armatures 3sw1 and 3sw2 extends the calling circuit direct to the relay set of the junction selected, while relay 3HR opens the circuit to the rotary magnet at armature 3hr2 and locks over its right-hand winding for the remainder of the connection. It should be explained that relay 3HR is slow to operate in order to allow sufficient time for relays 3H and 3DS to lock to the holding and guarding earth returned over the P wiper from the junction relay set.

If all the outlets are engaged, the wipers rotate to the 11th step where the cam springs 3S1 to 45 3S3 are operated; springs 3S1 provide a locking circuit for relay 3G to cut off rotary hunting, springs 3S2 connect busy flash to the lower winding of relay 3A and springs 3S3 complete a busy hold circuit to relay 3B. The busy flash signal 50 consists of the alternate application of battery and earth via the lower winding of relay 3A to the positive line and produces the alternate operation of a supervisory relay in the operator's cord circuit. During the battery flash period, 55 relay 3A is released but the busy hold circuit is completed to the right-hand winding of relay 3B during this period in order that the connection shall be maintained.

Local numbers are obtained by dialling the 60 prefix digits 2 or 3 which determine the hundreds line group in which the final selector will test. If the digit 3 is dialled the selector steps to the third level where relay 3DC is operated over the vertical wiper and bank when relay 3C 65 releases at the end of impulsing. Relay 3DC thereupon locks and at its armature 3dc2 completes a circuit from armature 3b2 and the resting contacts controlled by armature 3ws1 for the release magnet 3ZM which restores the shaft 70 and wipers to normal. When the shaft and wipers are fully restored the springs 3N2 will again become normal whereupon relay 3WS is then operated and locked. Relay 3C is also re-operated over the springs 3N1. The next digit raises 75 the shaft and wipers to the level having access

to the required group of final selectors and when relay 3C releases at the end of the digit, a cut-in circuit is completed for the rotary magnet. The wipers are therefore stepped on to the first outlet and hunting for an idle selector takes place in a similar manner to the hunting operation which took place for an outlet to the adjacent exchange. Since relay 3WS is operated, however, relay 3SW remains normal when the switching relay 3H operates, and earth is therefore connected to the 10 negative wiper over armatures 3ws5, 3a2, 3sd2, 3h1 and 3sw3 to operate the line relay in the final selector. Relay 3HR is also operated from armature 3h3 and opens the circuit to relay 3DC at armature 3hr2 and during the slow releasing 15 period of the latter a momentary battery is extended over armatures 3dc3 and 3hr6 and the D wiper to operate the wiper switching relay in the final selector 2WS, (Fig. 11) which transfers the incoming wires to the set of wipers having 20 access to the second 100-line group. This battery is replaced by earth when relay 3DC restores but the wiper switching relay in the final selector remains locked and the earth is ultimately extended to the P wiper of the final selector to busy the called line. If, however, the 25 digit 2 had been dialled instead of 3 relay 3DC would not be operated, but the vertical wiper and bank would have completed a circuit for relay 3G. Relay 3G in operating locks over 30 armature 3g2 and at armature 3g1 completes a circuit for the release magnet whereupon the shaft and wipers are restored to normal and relay 3WS is operated thereby releasing relay 3G at armature 3ws1. The conditions are now the 35 same as after the dialling of the digit 3 except that relay 3DC is not operated and therefore the wiper switching operation in the final selector does not take place, and connection is therefore made with the wipers of the first 100-line 40 group.

The calling subscriber now dials the tens and units digits to set the final selector to the required line. If the called subscriber is free the 45 momentary battery connected back over the positive line from the final selector operates relay 3SD, which completes the locking circuit for itself and at armatures 3sd2 and 3sd3 extends the ringing circuit by way of the winding of relay 3F to the called subscriber's instrument. 50 During the ringing period a ring-back tone is connected to the lower speaking conductor to the calling subscriber to inform him that the called subscriber's bell is being rung. When the called subscriber replies, the ringing relay 3F 55 trips from battery superimposed on the ringing circuit and in opening its armature 3f1 completes a locking circuit for itself for the remainder of the connection. Relay 3F also at armatures 3f4 and 3f5 completes the transmission circuit between both subscribers, whereupon relay 3D is 60 operated over the lines in series with the called subscriber's instrument, and at armatures 3d1 and 3d2 reverses the battery to the incoming junction for metering or supervisory purposes. 65

If the called subscriber is engaged, the momentary battery is not connected to the positive conductor and instead earth is removed from the wiper P so that relays 3H and 3DS in the incoming selector are released. Relay 3HR however remains held, and a busy flash signal is returned over the incoming junction to actuate the supervisory apparatus in the operator's cord circuit.

Under these conditions, a tone is superim- 75

posed on the battery flash circuit in order to inform the operator that the called subscriber is busy, thereby differentiating between the all-trunk-busy condition previously described.

- 5 When relay 3H restores, the short-circuit is removed from the left-hand winding of relay 3F, which thereupon operates and in turn at armature 3f3 completes a circuit over both windings of relay 3SD, which locks. At the same time the 10 holding circuit to the final selector is opened at the armatures 3h7 and 3h8 so that relays 2A and 2B therein release, but since earth remains connected to the D wiper at the incoming selector, relay 2H in the final selector is operated and 15 locked in the manner previously described to prepare the cut-in circuit over the busy condition. The actual talking circuit is, however, held open at this time at the contacts of relay 3h1 and 3h8 in the incoming selector.
- 20 To offer the call, the operator presses a button at her position, which momentarily connects earth to one of the incoming lines, thereby upsetting the balance of the differential relay 3OC in the incoming selector, which thereupon operates over one of its windings and at armature 3oc1 25 operates relay 3G over both its windings in series. When the operator releases the button, relay 3H then operates in series with relay 3G over a circuit which may be traced as follows: earth at 30 armature 3b2 (Fig. 13), springs 3NR1, armature 3sd6, winding of relay 3H, armatures 3sd5 and 3g2, windings of relay 3G in series to battery.

Relay 3H thereupon operates and at armature 3h1 locks in series with the vertical magnet 3VM, 35 thereby shunting relay 3G, which releases. The offering circuit is thus completed to the busy connection and relay 3D is operated over both its windings in series with armatures 3f2, 3sd4 and 3ds4 to provide supervision to the operator. 40 If the call is accepted, the operator instructs both subscribers to clear down, and when this is done battery from the required subscriber's line circuit is extended over the P wiper of the final selector in series with the D wiper of the 45 first selector via armatures 3h2, 3sd6 and 3hr1 to operate relay 3DS, which locks. Relay 3DS thereupon connects direct earth to the D wiper, which extends to the P wiper at the final selector to guard the called line. In the incoming selector, 50 relay 3D is released upon the opening of the loop circuit to provide supervision to the operator that the line is now clear, whereupon she again depresses the button previously referred to and relay 3OC again operates. This time relay 55 3OC shunts down relay 3F and ringing is extended to the required subscriber's circuit. From this point the connection proceeds as described in the case of an ordinary connection.

If digits 2 or 3, which correspond to local connections are followed by digits for which no final selector group is allocated, for example, digits 5 to 9, relay 3G is operated over springs 3rm, armature 3ws3 and the vertical bank and wiper 3VW when the wipers make their first rotary 65 cut-in, and regardless of potential picked up over the test wiper P, the wipers are caused to rotate automatically to the eleventh position, where a busy signal is returned in the manner already described.

70 Similarly, in case the digit 1 is inadvertently dialled, relay 3WS will not be operated and consequently when relay 3C releases at the end of

the digit, a circuit is completed over armatures 3hr2, 3b1, 3c2 and 3ws6 for the release magnet 3ZM so that the shaft and wipers are restored to normal.

The release of the connection is under the control of the calling party, and is brought about when he replaces his receiver on the switchhook. When this is done, the loop circuit over the incoming negative and positive conductors is opened so that relay 3A restores, and is followed shortly afterwards by relay 3B. Relays 3SD and 3H also release after a short interval.

Relay 3HR is also restored after its slow period, and a circuit is then completed for the release magnet 3ZM over armatures 3hr2 and 3b1 and the operated off-normal springs 3N3.

What is claimed is:

1. In a telephone system, subscribers' lines, primary finders having access to said lines and responsive to the initiation of calls over said lines for extending connections therefrom, overflow finders having access to said lines and operable to extend calls therefrom only when the primary finders are all busy, secondary finders having access to said overflow finders for extending connections from the overflow finders, incoming trunk lines from another exchange, said secondary finders also having access to and operable to extend calls received over said trunk lines.

2. In a telephone system, subscribers' lines and trunk lines, primary finder switches having access to said subscribers' lines, overflow finder switches having access to said subscribers' lines when all of the primary finders are in use, secondary finder switches having access to said trunk lines and to said overflow finders, common control apparatus for the primary finders, said apparatus having means for marking a contact in the banks of the secondary finder switches corresponding to the primary finder operated, and means in the secondary finder for subsequently supplying a holding potential back to the primary finder over the same bank.

3. In a telephone system, groups of subscribers' lines and trunk lines, a plurality of groups of primary finder switches each having access to a group of subscribers' lines, overflow finder switches having access to said subscribers' lines only when all of said primary switches are in use, secondary finder switches having access to said trunk lines and also to said overflow finders, means responsive to the initiation of a call from a line in one group for starting two finders of the group having access thereto, and means responsive to the simultaneous initiation of calls by lines in two groups for starting only one finder in each group of finders having access to the group in which a call is initiated.

4. In a telephone system, subscribers' lines, a plurality of groups of primary finder switches each having access to a corresponding group of said subscribers' lines, overflow finder switches having access to said lines only when said primary finders are all busy, common control apparatus for controlling any of said primary finder switches, and means responsive to the initiation of a call over one of said lines for operating a plurality of sets of said common control apparatus to control the operation of finders in the group having access to the calling line.

REGINALD TAYLOR.
GEORGE THOMAS BAKER.
